UNITED STATES PATENT OFFICE.

THOMAS BENFIELD, OF NEWARK, NEW JERSEY.

DESIGN FOR A WATCH-CASE.

SPECIFICATION forming part of Design No. 21,487, dated April 19, 1892.

Application filed March 17, 1892. Serial No. 425,370. Term of patent 7 years.

To all whom it may concern:

Be it known that I, THOMAS BENFIELD, a subject of Her Majesty the Queen of Great Britain, residing at Newark, in the county of 5 Essex and State of New Jersey, have invented and produced a new and original Design for Watch-Cases, of which the following is a specification, reference being had to the accompanying drawings, forming part thereof.

Figure 1 is a plan view of a watch-case, showing my design. Fig. 2 is a sectional view thereof, taken on the line X X of Fig. 1.

The leading or material feature of my design consists of a series of ribs A, disposed or arranged as shown in Fig. 1, being curved in their length and spread out in fan shape and

convex in cross-section, as shown in Fig. 2, one portion of the case near its lower end being left plain, as shown at B. The several portions, it is manifest, may be engraved, 20 chased, or otherwise ornamented, if desired.

This design is applicable to lockets and other similar articles.

Having described my invention, what I claim as new, and desire to secure by Letters 25 Patent, is—

The design for a watch-case, as herein shown and described.

THOMAS BENFIELD.
